BELT BUCKLE

Charles D. McDonald, Dallas, Tex.

Application October 18, 1948, Serial No. 149,161
Term of patent 14 years

(Cl. D17—1)

To all whom it may concern:

Be it known that I, Charles D. McDonald, a citizen of the United States of America, residing at Dallas, in the county of Dallas and State of Texas, have invented a new, original, and ornamental Design for Belt Buckles, of which the following is a specification, reference being had to the accompanying drawing, forming a part thereof.

Fig. 1 is a front elevational view of a belt buckle made in accordance with this design,

Fig. 2 is a rear elevational view of the belt buckle,

Fig. 3 is a side elevational view of the belt buckle taken from the right hand side of Fig. 1,

Fig. 4 is an end elevational view of the belt buckle taken from the top of Fig. 1, and

Fig. 5 is an end elevational view of the belt buckle taken from the bottom of Fig. 1.

The essential features of my design reside in the parts shown in full lines.

I claim:

The ornamental design for a belt buckle, as shown and described.

CHARLES D. McDONALD.
